Frank A. Cutler,

ATTORNEY.

Patented May 13, 1924.

1,494,105

UNITED STATES PATENT OFFICE.

EDWARD H. ELDER, OF CHICOOPEE FALLS, MASSACHUSETTS.

GUN.

Application filed March 22, 1923. Serial No. 626,979

To all whom it may concern:

Be it known that I, EDWARD H. ELDER, a citizen of the United States of America, and a resident of Chicopee Falls, in the county of Hampden and State of Massachusetts, have invented certain new and useful Improvements in Guns, of which the following is a specification.

My invention relates to improvements in breech-loading guns, and resides in a novel frame, peculiar shell-extractor means, a block at the front end of the frame, which block is recessed to receive and locate a lug on the barrel, means to secure said barrel in place on said block, and a resilient abutment that acts through intervening parts and members on the hand-lever, the aforesaid elements being arranged and combined with other elements which are old to make up a complete gun, all as hereinafter set forth.

The method of making the aforesaid frame is also comprehended in the invention.

One object of my invention is to provide for a gun a very inexpensive, yet strong and durable, frame which affords housings for the contiguous ends of the stock and fore-wood, and serves in the usual capacity as supporting and enclosing means for the lock, firing, and extracting mechanisms. This frame also provides a support for the breech terminal of the barrel, and makes it possible to secure said barrel to said frame by means of a bolt passed upwardly through said frame near the forward end thereof.

A further object is to provide a swinging or rocking breech piece with a projection that is adapted to throw out or force the extractor rearwardly when the gun is "opened," thus effecting a saving in parts and expense, without sacrificing anything to efficiency.

In time and due to wear the parts become loose so that the hand lever of the gun, when in closed position, drops away from the frame, instead of remaining in contact therewith as it should, and hangs loosely with more or less vibration as the gun is handled and moved about, and another object is to overcome this objection, which I do by providing means for taking up lost motion and retaining said lever against said frame at all times when in closed position.

Still other objects and advantages will appear in the following description.

Although some or all of the features of

this invention might be applied to shot-guns they are especially designed for and intended to be applied to rifles.

I attain the objects and secure the advantages of my invention by the means illustrated in the accompanying drawings, in which—

Figure 1 is a vertical or longitudinal section through a rifle wherein my improvements are embodied, the greater portions of the stock, barrel, and fore-wood of the rifle being broken off; Fig. 2, a generally similar view to the preceding view, but illustrating the operation of the movable parts and members; Fig. 3, a front end elevation of the U-shaped frame; Fig. 4, a side elevation of said frame, and, Fig. 5, a plan of the frame blank.

Similar reference characters designate similar parts throughout the several views.

The old parts of the rifle illustrated in connection herewith, and in connection and combination with which my improved features are used, are enumerated and somewhat briefly described as follows: A breech 1 and a retaining screw or bolt 2 therefor, a barrel 3, a fore-wood 4, a hammer 5, a trigger 6, a double spring 7 for said hammer and trigger, a breech-block 8, a firing-pin 9, an operating lever 10 provided with a handle 11, a link 12, and an extractor 13. The bolt 2 extends lengthwise through the stock 1. The bore of the barrel 3 is enlarged at the rear terminal to form a chamber 14 for the cartridge. The rear end of the chamber 14 is enlarged, as at 15, to provide space for the rim of the cartridge, and the barrel 3 is cut away in the usual manner to accommodate the extractor 13. The extractor 13 occupies a position which enables the same, when actuated rearwardly, to carry with it and partially remove from the chamber 14 the cartridge or cartridge shell. The extractor 13 has a rearwardly-extending stem 16 slidably arranged in a passage in the barrel 3 beneath and parallel with the axis of said barrel. The stem 16 is prevented from rotating by means of a screw 17 and entering a slotted or flattened part 18 of said stem. It is necessary to prevent the stem 16 from rotating in order that the cartridge-shell-engaging part, at the top of the extractor 13, shall always be in operative position.

The firing-pin 9 is received in an approximately horizontal passage in and through the breech-block 8, and the latter when

closed locates said firing-pin in position to strike the rim of the cartridge at a point adjacent to the bottom edge thereof. The action of the firing-pin 9 will be clearly understood from the drawings. The firing-pin is slotted at 19, and a pin 20 in the breech-block 8 extends through the slot to limit the rearward movement of said firing-pin.

10 The breech-block 8 has at the bottom a forward extension 21 which is beneath the breech portion of the barrel 3.

The link 12 at the upper terminal is pivotally connected at 22 with the breech-block 8, and at the lower terminal at 23 with the contiguous terminal of the lever 10. The link has a nose 24 for engagement with the adjacent face of the hammer 5. There are two trigger notches 25 on the bottom of the 20 hammer 5.

The new features comprise a U-shaped, sheet-metal frame 26 provided with rear and front retaining blocks 27 and 28, respectively, the top of the front block being recessed at 29 to receive a lug 30 on the bottom of the barrel 3 in advance of the lug or part of said barrel in which the extractor stem 16 is located, and said front block being provided on the back side with a 30 resilient abutment 31; a bolt 32 by means of which said barrel is securely fastened to said front block; and an extractor-operating finger 33 rising from the rear end of the breech-block extension 21.

35 The frame 26 is made by stamping out of sheet-metal a blank in substantially the form illustrated in Fig. 5, and cutting in the longitudinal center of such blank openings 34, 35, and 36, the first and third of such 40 openings being respectively in advance of and behind the second of such openings, after which such blank is bent along lines on both sides of and parallel with the aforesaid longitudinal center to form a bottom and parallel sides, substantially as shown in Figs. 3 and 4. The bolt 32 has at the 45 lower end a head 37, and the opening 34 in the frame 26 is provided to receive the upper portion of such head. The lever 10 is received and operates in the opening 35. In stamping out the blank for the frame 26 and cutting the opening 35, oppositely-disposed lugs 38 are left, and the lever 10 is pivotally connected at 39 with said frame 50 immediately adjacent to said lugs. The lugs 38 are provided to augment the frame at the bottom and permit the pivot pin 39 to be inserted in the sides of said frame at lower points than would be possible in the 55 absence of such lugs. The trigger 6 is received and operates in the opening 36, and said trigger is pivotally connected at 40 with the sides of the frame.

The retaining blocks 27 and 28 fit the 60 space between the sides of the frame 26, and

are securely riveted to said sides, there being three rivets 41 for said first-named block and two rivets 41 for said second-named block. The frame 26 thus reenforced with the blocks 27 and 28 is sufficiently strong, rigid, and durable for the purpose for which the same is designed, is practically equal to a forged frame or one made of a malleable casting, and no milling operations are required, as in the case of either the forged or malleable-iron frame.

The block 27 is angular, consisting of an approximately vertical arm and an approximately horizontal arm, and has at the top of the rear end an overhanging part 42. The horizontal arm extends forwardly from the vertical arm of the frame 26. The rear end of the part 42 is flush with the rear edges of the sides of the frame 26, and such part completes a housing for the forward end of the stock 1, as clearly shown in Fig. 1, such forward end being received between the bottom of said frame and said part 42, and between the sides of said frame, behind the vertical arm of the block 27. The bolt 2 extends clear through the stock 1 and is tapped into the vertical arm of the block 27.

The block 28 is set in a short distance from the extreme front end of the frame 26, for the purpose of providing a housing for the rear-end portion of the fore-wood 4, such portion being received between the bottom of said frame and the bottom of the barrel 3, and between the sides of said frame. The bolt 32 extends upwardly through the opening 34 in the frame, and through a suitable bore with which the block 28 is provided into the lug 30 and the barrel 3 above said lug, being tapped into said lug and barrel. The head 37 of the bolt 32 enters the opening 34 and bears against the bottom of the block 28. The barrel 3 is drawn down tightly onto the block 28, with the lug 30 in the recess 29, and there securely and rigidly held, by means of the bolt 32. The bolt head 37 may be provided with a ring 43 to facilitate the removal of the bolt 32 when it is desired to disengage the barrel 3, and the replacing of said bolt after said barrel has been returned to normal position.

The extension 21 is pivotally connected adjacent to its rear terminal, at 44, with the sides of the frame 26, it being understood that said extension and the breech-block 8 are received with a sliding or operating fit between the sides of the frame 26, as also are the lever 10, the lower portion of the hammer 5, and the upper portion of the trigger 6. The upper, free terminal of the 125 resilient abutment 31 bears against the heel of the extension 21 above the horizontal plane of the axis of the pivot pin 44, consequently said abutment has a constant tendency to swing the forward portion of said 130

extension with the breech-block 8 downwardly. When the breech-block 8 is in its elevated and closed position against the back end of the barrel 3, the pivot 23 is beyond 6 or at the left of a plane common to the axes of the pivots 22 and 39, thus locking said breech-block in place. With the parts disposed as just described, the handle 11 is in contact with the under side of the frame 26, 10 and said handle is retained in such position by the action of the abutment 31 on the extension 21, since the tendency of said abutment to force downwardly the rear end of said extension is transmitted through the 15 pivot 22 to the link 12, and the latter is thereby caused to exert through the pivot 23 force in a forwardly direction on the inner part of the lever 10, and, since said lever is mounted on the pivot 39, the lever crowds 20 said handle against said frame. The lever 10 is thus retained under a tension which prevents the handle 11 from dropping away from the frame. The parts and members are at this time disposed as represented in 25 the first view.

The hammer 5 is pivotally connected at 45 with the sides of the frame 26. Both the hammer 5 and the trigger 6 are controlled by the spring 7 in the usual manner, and the 30 notched base of said hammer and the engaging finger of said trigger cooperate in the usual manner.

The finger 33 extends upwardly in front of the extractor stem 16 in position to actuate said stem forwardly when the breech-block 8 is swung downwardly, and so acts— see Fig. 2.

The openings in the sides of the frame 26 for the rivets 41, and the pivots 44, 39, 45, 40 and 40, are drilled in said sides after the blank has been bent into proper shape, instead of being initially cut in the blank, because in the latter event oppositely-disposed openings might not be in exact alignment 45 with each other.

The gun is opened by grasping the handle 11 and carrying the same downwardly into the position shown in Fig. 2, the lever 10 then being rocked on the pivot 39 in the direction to carry the pivot 23 rearwardly

50 through the plane common to the axes of the pivots 22 and 39 and between said pivots 22 and 39, and still further rearwardly and downwardly after leaving said plane. This 55 operation will require a little additional force initially or while the pivot 23 is approaching and passing through the afore- said plane, as will be readily understood. The first result produced by the downward

60 movement of the handle 11 is to cause the hammer 5 to be rocked on the pivot 45, against the resiliency of the spring 7, until the finger of the trigger 6 enters the foremost notch 25. This is the half-cock position of the hammer. The hammer is half-

cocked by the action thereon of the nose 24 of the link 12 while the pivot 23 is crossing the aforesaid plane, or directly after such event. As soon as the hammer 5 is moved out of the customary locking position relative to the breech-block 8, the downwardly-moving lever 10, acting through the link 12, begins to draw down said breech-block and finally actuates the same into the position shown in Fig. 2. The rocking movement of 70 the breech-block extension 21 on the pivot 44, at this time, causes the finger 33 to be carried into contact with the front end of the stem 16, and to force the latter rearwardly and with it the extractor 13, the 75 movement of said extractor in this direction being limited by the front face of the breech-block. The extractor slides the cartridge or shell from the chamber 14 far enough to enable the same to be grasped with the thumb and finger and removed entirely. The cartridge is inserted in the chamber 14 with the bottom part of the rim of the cartridge shell in engagement with the rearwardly-disposed extractor 13, and the 80

85 breech-block 8 is closed by grasping the handle 11 and swinging the same with the lever 10 upwardly. This action simultaneously causes the extractor to be moved by the breech-block forwardly and the finger 33 to be swung away from the advancing stem 16. The cartridge is forced completely into the chamber 14 by the rising breech-block, and finally the latter is locked in closed position 90 by the pivotal connections between the lever 10 and the breech-block. The gun is now in readiness to have the hammer drawn back to full-cock, and then to be released by pulling the trigger 6, thus firing the cartridge 95 through the medium of the firing-pin 9.

100 As the handle 11 approaches the bottom of the frame 26, in closing the breech-block, the pivot 23 is forced through and forward of the plane connecting the pivots 39 and 22, which causes the parts to be locked, and, 105 through the medium of the resilient abutment 31, said handle to be retained in contact with said frame, all in the manner previously described in detail.

The mechanism can, of course, be operated 110 in substantially the manner hereinbefore described without a cartridge or cartridge shell.

More or less change in the shape, size, 115 construction, and arrangement of some or all of the parts of this invention may be made without departing from the spirit of the same, or exceeding the scope of what is claimed.

What I claim as my invention, and desire 125 to secure by Letters Patent, is,—

1. As an improved article of manufacture, an open-top gun frame consisting of a piece of sheet-metal bent to form bottom and side members, and having trigger, operating- 130

- lever, and bolt openings cut in such bottom member.
2. As an improved article of manufacture, an open-top gun frame comprising a piece of sheet-metal bent to form bottom and side members, and having trigger, operating lever, and bolt openings in the bottom member, retaining blocks inserted between said side members, and transverse members passing through said side members, and said blocks to secure the latter to the former.
3. As an improved article of manufacture, a gun frame comprising a piece of sheet-metal bent to form bottom and side members with openings in said bottom for working parts, and a retaining block secured within said frame adjacent to the rear end thereof, and forming with said frame a housing for the contiguous end of a stock.
4. As an improved article of manufacture, a gun frame comprising a piece of sheet-metal bent to form bottom and side members with openings in said bottom member for working parts, and a retaining block secured within said frame adjacent to the forward end thereof, and forming with said frame a housing for the contiguous end of a fore-wood.
5. As an improved article of manufacture, a gun frame comprising a piece of sheet-metal bent to form bottom and side members with openings in said bottom member for working parts, and retaining blocks secured within said frame adjacent to the ends thereof, and forming with said frame housings for the reception of contiguous portions of a stock and fore-wood.
6. The combination, in a gun, with a frame having an integral resilient member, of a breech-block having a part pivotally connected with said frame and in engagement with said resilient member, and operating means for said breech-block.
7. The combination, in a gun, with a frame provided with a resilient member, of a breech-block having a part pivotally connected with said frame and in engagement with said resilient member, a lever pivotally connected with said frame, said lever having a handle, and a link pivotally connected with said lever and with said breech-block, the construction and arrangement of parts being such that, when said breech-block is raised into closed position by said lever and link, the pivotal connection between said lever and link passes the plane common to the axes of the pivotal connections between said lever and frame and said link and breech-block, and said resilient member tends to rock said breech-block downwardly, and, through the medium of said link, actuate said lever in the direction to force said lever against said frame.
8. The combination, in a gun, with a sheet-metal frame, a retaining block inserted between the sides of and secured to said frame, and slotted to form an integral resilient abutment at the back end, of a breech-block having a part pivotally connected with said frame and in engagement with said abutment, and operating means for said breech-block.
9. The combination, in a gun, with a frame, a retaining block secured to said frame, and provided with a resilient abutment, of a breech-block having a part pivotally connected with said frame and in engagement with said abutment, a lever pivotally connected with said frame, said lever having a handle, and a link pivotally connected with said lever and with said breech-block, the construction and arrangement of parts being such that, when said breech-block is raised into closed position by said lever and link, the pivotal connection between said lever and link passes the plane common to the axes of the pivotal connections between said lever and frame and said link and breech-block, and said abutment tends to rock said breech-block downwardly, and, through the medium of said link, actuate said lever in the direction to force said handle against said frame.
10. As an improved article of manufacture, a gun frame comprising a piece of sheet-metal bent to form bottom and side members with openings in said bottom for working parts, and a retaining block secured within said frame adjacent to the forward end thereof, said block being slotted to form an integral resilient abutment at the back end.
